16,17-[3',1'-(3'-CARBOXY 2' PYRAZOLINO)] 20
PREGNEN-20-ONES

George P. Mueller, Park Ridge, Ill., assignor to G. D. Searle & Co., Chicago, Ill., a corporation of Illinois

No Drawing. Application February 1, 1955,
Serial No. 485,609

5 Claims. (Cl. 260—239.5)

The present invention relates to a new group of pentacyclic pyrazolinecarboxylic acids and, more particularly, to 16,17-[3',1'-(3'-carboxy-2'-pyrazolino)]-pregnen-20-ones containing an oxygen atom attached to the carbon atom in position 3 of ring A.

The compounds which constitute this invention can be represented by the structural formula

wherein one of the bonds linking the carbon atom in position 5 to the carbon atoms in position 4 and 6 is unsaturated and wherein X= is a member of the class consisting of

and

In my copending application Serial No. 349,984, filed April 20, 1953, of which the present application is a continuation-in-part, there is described the preparation of the lower alkyl esters of the acids claimed herein from which they are derived by conventional deesterification procedures such as by heating with an alkali metal hydroxide in an aqueous alcoholic solution.

The acids of this invention can also be used in the form of their lower alkali metal, lower alkaline earth metal, ammonium, and amine salts. The compounds of this invention have valuable pharmacological properties. They are effective cardiovascular drugs and cause a decrease in hypertensive blood pressure levels. They differ from their lower alkyl esters in their hormonal action. Specifically, they inhibit some of the undesirable side effects of cortisone without interfering with the therapeutic actions of that hormone such as the anti-rheumatic effect. Cortisone is known to interfere with some of the defense mechanisms of the organism against the spread of infection and this is a serious limitation on its therapeutic applicability. On co-administration with cortisone, the acids of this invention and their salts prevent the atrophying effect of cortisone on the lymph nodes and the sinus. It appears that this effect is limited to the acids and their salts and is lost on esterification since the lower alkyl esters do not produce this anti-cortisone effect.

The following examples describe in further detail certain of the compounds which constitute this invention and methods for their preparation. However, the invention should not be construed as limited thereby in spirit or in

2

scope. It will be obvious to chemists skilled in the art that numerous modifications in methods and materials may be adopted without departing from the scope of the invention. In these examples, quantities of materials are indicated in parts by weight and temperatures in degrees centigrade.

EXAMPLE 1

16,17-[3',1'-(3'-carboxy-2'-pyrazolino)]-Δ⁵-pregnen-3-ol-20-one

A mixture of 71 parts of 3-acetoxy-Δ^{5,16}-pregnadien-20-one and 103 parts of ethyl diazoacetate is heated on an oil bath at 115-120° C. for 75 minutes. There is an evolution of gas and the crystal cake melts slowly. On cooling a crystalline cake forms again. Successive recrystallizations from benzene and from methanol yield the ethyl ester of 3-acetoxy-16,17-[3',1'-(3'-carboxy-2'-pyrazolino)]-Δ⁵-pregnen-20-one, melting at about 217-222° C. with decomposition.

A solution of 25 parts of potassium hydroxide in 50 parts of water and 40 parts of methanol is refluxed with a solution of 5 parts of the ethyl ester of 3-acetoxy-16,17-[3',1'-(3'-carboxy-2'-pyrazolino)]-Δ⁵-pregnen-20-one in 800 parts of methanol for one hour under nitrogen. Then 400 parts of water are added and the mixture is chilled. A sufficient amount of dilute hydrochloric acid is added to the filtrate to lower the pH to about 4. The resulting solution is partially concentrated in vacuo. The precipitate is collected on a filter. The 16,17-[3',1'-(3'-carboxy-2'-pyrazolino)]-Δ⁵-pregnen-3-ol-20-one melts at about 241-244° C. The compound has the structural formula

EXAMPLE 2

3-acetoxy-16,17-[3',1'-(3'-carboxy-2'-pyrazolino)]-Δ⁵-pregnen-20-one

One part of 16,17-[3',1'-(3'-carboxy-2'-pyrazolino)]-Δ⁵-pregnen-3-ol-20-one is treated with 20 parts of acetic anhydride and 20 parts of pyridine at room temperature for 20 hours and then poured on ice and water. The mixture is extracted with ether and the ether extract is washed with dilute hydrochloric acid and water, dried over anhydrous sodium sulfate and evaporated. Crystallization from benzene and petroleum ether yields the 3-acetoxy-16,17-[3',1'-(3'-carboxy-2'-pyrazolino)]-Δ⁵-pregnen-20-one in crystals melting at 233.0-233.6° C. The specific optical rotation of a dioxane solution is [α]_D=+209.5°. The ultraviolet absorption spectrum shows a maximum at 272 millimicrons with a molecular extinction coefficient of 8408. The compound has the structural formula

3
EXAMPLE 3

3 - butyroxy - 16,17 - [3',1' - (3' - carboxy - 2' - pyrazolino)1 - Δ^5 - pregnen - 20 - one

A mixture of 1 part of 16,17-[3',1'-(3'-carboxy-2'-pyrazolino)1- Δ^5 -pregnen-3-ol-20-one, 31 parts of butyric anhydride and 30 parts of pyridine is maintained at room temperature for 24 hours and then poured into ice water. The resulting mixture is extracted with ether and the ether extract is washed successively with dilute hydrochloric acid and water, dried over anhydrous calcium sulfate and evaporated. Crystallization from benzene and petroleum ether yields 3-butyroxy-16,17-[3',1'-(3'-carboxy-2'-pyrazolino)1- Δ^5 -pregnen-20-one. The ultraviolet absorption spectrum shows a maximum at about 272 millimicrons with a molecular extinction coefficient of 8200. This compound has the structural formula

EXAMPLE 4

16,17 - [3',1' - (3' - carboxy - 2' - pyrazolino)1 - Δ^4 - pregnene - 3,17 - dione

A mixture of 31.2 parts of 16-dehydroprogesterone and 25 parts of ethyl diazoacetate is heated at 125° C. for an hour and the resulting gummy product is taken up in 1400 parts of hot ether. The ether solution is evaporated to yield the ethyl ester of 16,17-[3',1'-(3'-carboxy-2'-pyrazolino)1- Δ^4 -pregnene-3,17-dione as a yellow oil.

Ten parts of this oily product are refluxed with 50 parts of potassium hydroxide in 100 parts of water and 1700 parts of methanol for an hour under nitrogen. Then 1000 parts of water are added and the mixture is chilled. A sufficient amount of dilute hydrochloric acid is added to the filtrate to lower the pH to about 4 and the resulting solution is partially concentrated under vacuum. A precipitate is formed which is collected on a filter. There is thus obtained the 16,17-[3',1'-(3'-carboxy-2'-pyrazolino)1- Δ^4 -pregnene-3,17-dione which has the structural formula

The infrared absorption spectrum shows maxima at 5.80, 60 6.02, and 6.40 microns.

What is claimed is:

1. A member of the class consisting of the compounds of the structural formulas

and

4

wherein X is a member of the class consisting of hydrogen and (lower alkyl)-CO—radicals.

15 2. A compound of the structural formula

30 3. A compound of the structural formula

35 4. A compound of the structural formula

40 5. A compound of the structural formula
